UNITED STATES PATENT OFFICE

2,229,101

THERMAL INSULATION

Joseph M. Le Grand, Heathsville, Va., assignor
of one-fourth to John Randolph Tucker, Rich-
mond, Va.

Application March 8, 1935, Serial No. 10,040

8 Claims. (Cl. 189—1)

My invention relates generally to thermal insulation and has to do more particularly with insulation structure including one or more metallic sheets so arranged in a space as to insulate 5 against the transfer of heat therethrough.

One of the objects of my invention is to provide an improved insulating structure of the foregoing character which is simple in construction, is easy and inexpensive to manufacture and ins- 10 stall, and which insures high insulation efficiency at all times.

Another object is to provide an insulation structure including one or more metallic sheets formed of a material possessing relatively low 15 reflective characteristics when exposed to visible radiation and relatively high reflective characteristics when exposed to infra-red radiation and which is also adapted to resist the effects of moisture (such as rusting and the like) without affecting its reflective characteristics.

A further object is to provide an insulation structure of the foregoing character comprising one or more comparatively stiff metallic sheets having the sides thereof permanently coated with 25 an alloy including lead and tin and in which at least seventy (70) per cent lead is used.

Other objects and advantages will become apparent from the following description, and by reference to the drawing wherein—

30 Figure 1 is a horizontal section through a portion of a walled structure having my invention applied thereto;

Fig. 2 is a section taken substantially on line 2—2 of Fig. 1; and

35 Fig. 3 is a separated perspective view of one of the metallic insulation units shown in Figs. 1 and 2.

In the drawing, I have shown my invention applied to a structure that may well serve as a 40 refrigerator cabinet; however, it is to be understood that this invention is applicable to all forms of structure in connection with which similar thermal insulation conditions are to be met.

The cabinet structure shown in Figs. 1 and 2 45 includes an inner wall 10 and an outer wall 11 supported in any desired fashion by upright stud members 12 and horizontal members 13. The walls 10 and 11 and their supporting members may be formed of any suitable material.

50 The support members 12 and 13 are formed, preferably, however, from some suitable non-conducting material so as to minimize the transfer of heat at that point by conduction. By arranging the walls and their supports in the manner stated, 55 I provide wall spaces 14 to be insulated against

the transfer of heat therethrough by radiation, convection, and conduction. The structure for accomplishing such insulation will now be described.

An insulating unit 15 (Fig. 3) is inserted in 5 each space. This unit preferably takes the outline shape of the space 14 and it is comprised of a peripheral frame member 16 of such size and shape as to extend around and along the walls defining the top, bottom and ends of the space 14. 10 The frame 16 may be formed of any suitable material having some flexibility and which may be preformed to serve as a support for a plurality of metallic sheets 17 and 18. The frame member 16 is normally of slightly greater width, or depth, 15 than the space 14 so that, when it is inserted within such space, its side edges 16a firmly and yieldably grip the inner and outer walls 10 and 11 so that the unit 15 as a whole is retained in place against vibrational strains and stresses and 20 shocks.

The metallic sheets 17 and 18 may be formed of any suitable material of sufficient thickness and stiffness to retain preformed shape. Inexpensive iron or steel sheets may well serve the 25 purpose. The sheets 17 and 18 are covered throughout with a metallic coating adapted to resist the effects of moisture, such as rusting and the like, which coating provides the sheets with surfaces possessing relatively low reflective characteristics when exposed to visible radiation (radiation of wave lengths within the visible portion of the electromagnetic spectrum) and relatively high reflective characteristics when exposed to infra-red radiation (radiation of longer wave 30 lengths than the visible portion of the electromagnetic spectrum). In using the expressions "relatively low" and "relatively high" above, it is to be understood that this may mean low and high relative to each other, or low and high relative to material such as aluminum or other bright surfaced materials or coatings. More particularly, the sheets 17 and 18 are provided with a permanent coating in the form of an alloy consisting of lead and tin. This alloy contains a 45 greater percentage of lead than tin, and not less than seventy (70) per cent of lead. I have found that excellent results may be obtained by using an alloy consisting of eighty-five (85) to eighty-seven (87) per cent lead and thirteen (13) to 50 fifteen (15) per cent tin, in which case the surfaces of the sheets not only resist the effect of moisture but they also have the reflective characteristics above stated. The coating may be applied to the sheets at any desired stage of 55

manufacture and in any suitable manner as, for example, by passing the same through a molten bath consisting of the requisite proportions of lead and tin. Such sheet iron coated with an alloy of tin and lead is known as terneplate.

Sheets 17 and 18 are supported by the frame member 16 at their edges only. To this end, the frame member 16 is provided with grooves 19 in which the edges of the sheets are snugly received and secured. In the use of this form of support, the sheets divide the space 14 into a plurality of substantially parallel spaces 20, 21 and 22 that are unobstructed throughout and are substantially sealed apart from each other by the frame member 16.

The sheets 17 and 18 may be spaced with respect to each other and to the walls 10 and 11 in any desired manner to suit the particular conditions of use. However, where adaptable, I prefer to space these sheets in the manner disclosed in my prior Patent No. 1,910,703.

It is believed that the operation of my invention will be readily understood from the foregoing. In the use of my invention I have found that insulation against the transfer of heat by radiation and/or convection and/or conduction is minimized to a highly efficient extent; and that, also, when the metallic sheets 17 and 18 are exposed to moisture, they resist rusting and other detrimental effects so that the structure is capable of constant and indefinite use with substantially uniform insulation efficiency.

It will be appreciated from the foregoing that, while I have shown only one form of structure embodying my invention, changes in details and arrangement of parts may be made without departing from the spirit and scope of my invention as defined by the claims that follow. For example, the number of sheets employed in each unit may be varied. One or more may be used. The sheets may be spaced by any suitable form of frame member which is adapted to hold the sheets firmly in the proper spaced relation, which frame member passes only around the periphery of such sheets so as to leave the spaces defined thereby unobstructed substantially throughout. Also, the sheets 17 and 18 may have their surfaces divided into a plurality of angular and intersecting plane surfaces 23 as shown in Fig. 3, or they may be plain sheets with smooth surfaces.

I claim:

1. In structure of the class described, means forming a space to be insulated, and means for insulating said space comprising at least one metallic sheet mounted in said space in spaced relation to said space forming means and forming a plurality of disconnected spaces, said sheet having its surfaces that are exposed to said spaces covered with a metallic coating formed of lead and tin, a greater proportion of lead being employed and to an extent sufficient to provide a surface having relatively low reflective characteristics when exposed to visible radiation and relatively high reflective characteristics when exposed to infra-red radiation together with moisture resisting characteristics, and means for mounting said sheet in said space without obstructing said spaces in any substantial manner.

2. In structure of the class described, the com-

bination of spaced walls defining a space to be insulated, a plurality of metallic sheets mounted in said space in spaced relation with respect to each other and to said walls, said sheets being formed of a material of sufficient thickness and stiffness to retain preformed shape and being coated with an alloy consisting of not less than 70 per cent lead and the remainder tin providing a surface having relatively low reflective characteristics when exposed to visible radiation and relatively high reflective characteristics when exposed to infra-red radiation, and means for supporting said sheets in said spaced relation and whereby said space is divided into a plurality of spaces substantially sealed apart from each other. 15

3. In structure of the class described, the combination with spaced walls defining a space to be insulated, of insulation means mounted in said space including a plurality of commercial black steel sheets of substantially the length and width 20 of said space mounted therein in spaced relation with respect to each other and to said walls, said sheets having sufficient stiffness to retain preformed shape and having a rustproof surface of high heat reflectivity by being permanently coated with an alloy formed of at least 75 per cent lead and the remainder including tin, and means for mounting said sheets in said space in said spaced relation.

4. In combination, a pair of spaced walls and 30 thermal insulation therebetween, said insulation including a metallic sheet having sufficient stiffness to retain pre-formed shape and a dull dark surface having high heat reflectivity, and means for spacing the insulation sheet from both said walls, 35 said means including a member partly surrounding the edge surfaces of the insulation sheet and having its opposed edges resiliently engage the wall surfaces and be held thereby.

5. In a heat insulation unit, a sheet of terneplate of sufficient thickness and stiffness to retain preformed shape. 40

6. In structure of the class described, means forming a space to be insulated and means for insulating said space comprising a sheet of terneplate mounted therein with the spacing provided by said forming means being on opposite sides of said sheet. 45

7. A unit for use in heat insulating structures, comprising a metallic sheet having its surfaces 50 covered with a metallic coating formed of lead and tin, the greater proportion thereof being lead, and means for securing said sheet in place in a space to be insulated, said means including laterally flanged portions extending from said sheet 55 adjacent the ends thereof.

8. In a heat insulation unit, a body of supporting material of sufficient thickness and stiffness to retain preformed shape and a layer supported by said body comprising an alloy of lead 60 and tin, the lead content of said alloy being at least 70% thereof, said layer providing relatively low reflective characteristics when exposed to radiation of wave lengths within the visible portion of the spectrum and relative high reflective characteristics when exposed to radiation of wave lengths longer than those within the visible portion of the spectrum. 65
